UNITED STATES PATENT OFFICE.

NATHAN SPARER, OF SOMERVILLE, AND MAX HALPERSON, OF BOSTON, MASSACHUSETTS.

MACHINE FOR MAKING AND ASSEMBLING PLAITED BUTTONS.

Application filed April 11, 1924. Serial No. 705,746.

To all whom it may concern:

Be it known that we, NATHAN SPARER, a subject of the Government of Austria, and a resident of Somerville, in the county of 5 Middlesex and Commonwealth of Massachusetts, and MAX HALPERSON, a citizen of the United States, and a resident of Boston, in the county of Suffolk and Commonwealth of Massachusetts, have invented certain new and useful Improvements in 10 Machines for Making and Assembling Plaited Buttons, of which the following is a specification.

This invention relates to button making machines and more particularly to machines for making plaited buttons such as claimed in patent granted March 11, 1924 No. 1,486,309.

It is an object of the invention to form a certain portion of a button and prepare it for assembly with other, stock parts, in a simple and expeditious manner.

A further object of the invention is to form a certain portion of a button by the use of a male and female die, one of which is telescopic, and adapted to so manipulate the goods to be formed, that certain portions thereof are formed in advance of the remaining portions, and in such manner that material for the next succeeding portion to be formed, is positioned, prior to the formation thereof.

Another object of the invention is to form a certain portion of a button, such as an ornamental face, by the use of a male and female die, and while the goods is in said female die, to apply thereto a tie member, and while still in said die, to assemble the said face and attached tie member with other parts to make a completed button.

A still further object of the invention is to provide means to ensure the retention of the goods in the female die upon the retraction of a pressure exerting implement, whether the said implement is a die, or a tie attaching device.

It is also an object of the invention to produce a simple device for attaching a tie member to a formed button face, while the said face is still positioned in a forming die, the said device having means to center the tie member and temporarily hold it in place

preparatory to affixing the said member to the goods in the die.

The telescopic die and certain other parts 55 shown herein are the same as shown in the above named patent but not claimed therein, while others parts, so far as is known are new in this particular art.

It is not known that a telescopic die has 60 even been used in the manufacture of plaited buttons, prior to the application for the said patent.

Nor is it known that a device for applying a tie member to the back of a button face 65 has ever been used in connection with button forming and making machines, nor is it known that devices have ever been used heretofore, to retain a plaited button face in its forming die upon the withdrawal therefrom 70 of a pressure applying instrument or tool.

In view of the above, it is not the intention to limit this invention to the precise construction and arrangement shown as various changes might be made therein without departing from its spirit and scope. 75

The invention further consists in certain novel features of construction and arrangement of parts which will be fully understood from a description of the drawings 80 and the claims hereinafter given.

Of the drawings:

Figure 1 represents a view, partly in section, of a portion of a button forming and making machine showing the dies thereof as 85 about to plait material for the ornamental face of a button.

Figure 2 is a view similar to Figure 1 but showing a device adapted to apply a tie member to the material, as formed by the 90 dies shown in Figure 1.

Figure 3 is a view of the female die shown in Figures 1 and 2, showing the material in the die with a tie member secured thereto and a shell or body portion assembled therewith preparatory to the final button making operation. 95

Figure 4 is a view, in section, of a device adapted to receive the parts forming the back of the button, and in which the final 100 operation of button making is completed.

Figure 5 is a view in section of the devices of Figures 3 and 4 positioned for the final operation of button making.

Figure 6 is an enlarged face view of a plaited button such as might be made by the devices shown in Figures 1 to 5 inclusive.

Figure 7 is a section on the line 7-7
5 Figure 6.

Figure 8 is an underside view of the tie member affixing device shown in Figure 2.

Like characters represent like parts throughout the several figures of the drawings.

Referring to the drawings:

The drawings herewith represent one form of telescopic die, and consequently plaited button face, which may be made in accordance with the present invention, but it will be understood that the shape of the die may be changed to conform to the design of button face required.

It will also be understood that the means for retaining the goods in place in the female die upon retraction of the tie member affixing device, may be applied to the male die if required, but as this particular die does not require means of this sort, it is not herein shown in connection therewith.

As in the above patent, a solid female die 10 is detachably mounted in a suitable manner on a table or support 11, and beneath a telescopic die 12 which is composed of a plurality of spring pressed members 13, 14, and 15, and the relatively stationary housing 16.

For the best results the die 12 is heated in any usual or suitable manner, as for instance, by an electric heater 17, as conventionally illustrated in Figures 1 and 2.

With the material 18 for the button face, in position on the female die 10 and upon the descent of the die 12 into the die 10, the spring pressed members, 13, 14 and 15 will meet the material in the order named, followed by the end of the housing 16, whereby material for the center plait is first drawn inwardly, and thereafter, in order, material for each succeeding plait, until the end of the housing has pushed its material to the bottom of the receptacle in the female die 10. At this time the bottom of each of the spring pressed members will be approximately in a plane with the bottom or end of the housing 16, and the plaiting operation will have been completed.

The plaited button face is now ready to be assembled with other parts to make a completed button, and this may be done at once if desired, but preferably a tie member 19 is affixed to the inner surface of the plaited face before it is assembled, in order that the several plaits may not be later disarranged and the design distorted.

The female die 10 has slidably mounted thereon a sleeve 20 having a flange 21 provided with the rim 22, said sleeve 20 being secured to the said die 10 by means of the

pins 23 which enter slots 24 of the said sleeve and thereby permit a relative longitudinal movement between the die and sleeve for a limited distance.

In many instances it is advisable to apply the tie member to the plaited material before it has been removed from the female die, while in other instances it is not essential to do so, or even to apply a tie member at all.

The present invention includes the affixing of a tie member to the plaited material; and for this purpose a sleeve like member 25 has slidably mounted therein another slideable member 26 the two being held from separation by the screw 27 which may travel in an elongated depression of said member 26, a spring 28 normally retaining the said members in the position shown in Figure 2.

A plunger like member 29 slidably secured to the member 26 by screw 30, and backed by the spring 31, has a pin 32 extending from the center thereof upon which a tie member 19 is to be impinged to temporarily hold it in position preparatory to affixing it to the plaited material.

As a means of guiding the tie member into place on the plunger 29 and holding it there temporarily, other pins 33 see Figure 8 extending from the member 25 might be used in conjunction with said pin 32, or without it.

Preferably the metal of the member 25 adjacent the periphery of the plunger end, is cut away or bevelled as at 34, whereby a centering means is provided for the tie member in the absence of the pins 33, and little or no opportunity is presented for the accumulation of gum or adhesive which might occur if said member was not cut away, for it will be understood that the side of the tie member next to the plaited material is coated with an adhesive which would have a tendency to overflow and contact with and be deposited on the walls of the tube or cylinder in which the said plunger 29 plays.

With the tie affixing member, having a tie member 19 temporarily attached thereto, positioned as shown in Figure 2, the male die 16 may be caused to descend, whereupon the collar 35 of said die 16 will contact with and depress the member 26 until it in turn compresses spring 31 and forces the plunger 29 outwardly to thereby affix the previously moistened or gummed surface of the tie member, to the plaited material 18.

Upon the removal of the pressure of die 16, the springs 28 and 31 will cause the parts to resume their normal position shown in Figure 2, wherein the plunger 29 has been retracted, but leaving the tie member 19 affixed to the plaited material, the mem-

ber 25 resting on the material which it holds in place in the die 10 during the retracting movement of the plunger 29.

- The said member 25 is in this instance provided with spring pressed headed pins 40, two of which are shown but more may be used if necessary, which push outwardly, when the member 25 is removed from its position on the material 18, to thereby aid in freeing the member 25 from the material 18 in case it should adhere thereto and tend to pull the plaited material from the die 10.
- As before stated, similar pins may be used in connection with the male die 16 if occasion requires.

- After affixing the tie member to the plaited material, the die 10 may be removed from its seat on the support 11 and a shell 41 placed on the material and forced downwardly to cause the die 10 to slide in the sleeve 20 till the position Figure 3 is assumed.

The back portion of the body of the button comprising in this instance a wad 42, and cover of fabric or similar flexible material 43 is forced into the bore of a sleeve member 44 till it rests on an anvil 45.

- The said member 44 having a flange 46 and being slidably engaged with the anvil 45 by means of pins 47 extending from said sleeve into elongated guide holes in said anvil, the two parts being normally held in the position shown in Figure 4 by means of the spring 48.

- The anvil 45 may now be placed as seen in Figure 5 with the die 10 placed upon it and pressure applied by a plunger 49 causing the said die 10 to descend and to cause the front and back portions of the button to become united approximately as seen in Figure 7 of the drawings.

- The button shown herein is an ornamental one as well as a useful one and may be used in articles of clothing for decorative as well as useful purposes, and in such event the plaited face may be composed to textile fabric such as a garment may be made of, or of any suitable flexible material.

Having described the invention we claim:

1. In a machine for forming and assembling plaited buttons comprising a female die adapted to aid in embossing a design upon button face material; a male die comprising a plurality of relatively movable parts adapted to cooperate with said female die to emboss a design upon button face material, and adapted to enter said female die, with one portion of the design in advance of another; and means including said female die to assemble said button face material with the body of a button.
2. In a machine for forming and assembling plaited buttons, comprising a female die having a design cut in the face thereof; a
3. In a machine for forming and assembling plaited buttons, comprising a female die having a design cut in the face thereof; a male die comprising a plurality of relatively movable spring pressed parts each of which constitutes a portion of a design corresponding to the design of said female die, and having their operating portions arranged in different planes but adapted to assume a common plane when in said female die; means whereby all of said die portions may be advanced when the operating portions thereof are in the same plane; said male and female dies being adapted to emboss a design upon textile fabric; and means to assemble embossed textile fabric with the body of a button.
4. In a machine for forming and assembling plaited buttons, comprising a female die having a design cut in the face thereof; a male die comprising a like design and adapted to enter said female die to form a design unsupported in relief in textile fabric placed on said female die; means to affix a tie member to the exposed portions of textile fabric when formed in said female die; and means to assemble said formed fabric and attached tie member with the body of a button.
5. In a machine for forming and assembling plaited buttons, comprising a male die and a female die adapted to coact to form an unsupported raised design in flexible material; means coacting with said female die to affix a tie member to formed material; and means including said female die to assemble formed material with the body of a button.
6. In a machine for forming and assembling plaited buttons, comprising male and female dies adapted to form an unbolstered embossed design in flexible material; a plunger adapted to coact with said female die to affix a tie member to material formed by said dies; means to return said plunger to normal position after the affixing operation thereof; and means including said female die to assemble said formed material and an attached tie member, with the body of a button.
7. In a machine for forming and assembling plaited buttons, comprising a pressure operated male die and a female die adapted to form a raised design in flexible material;

- means to affix a tie member to material formed by said dies; means to retain material in formed position in said female die upon the retraction of said tie affixing means; means to cause the separation of said second means and material formed in said female die upon the retraction of said second means; and means including said female die to assemble formed material with the body of a button.
8. In a machine for forming and assembling plaited buttons, comprising a male die and a female die adapted to coact to form a raised design in textile fabric; means to affix a tie member to textile material while said material is positioned in said female die; means to retain said material in said female die upon the removal of said first means; and means including said female die to assemble said formed textile fabric with the body of a button.
9. In a machine for forming and assembling plaited buttons, comprising a male die and a female die adapted to form a raised design in flexible material; a plunger
10. In a machine for forming and assembling plaited buttons, comprising a male die and a female die adapted to form a raised design in flexible material; a plunger adapted to force a tie member upon flexible material held in said die; guide means for said plunger; means to position a tie member upon said plunger; means to detachably secure a tie member to said plunger; and means to assemble said formed flexible material and attached tie member with the body of a button.
- 15
10. In a machine for forming and assembling plaited buttons, comprising a male die and a female die adapted to form a raised design in flexible material; a plunger adapted to coact with said female die to affix a tie member to said flexible material while said material is in said female die; means to position and temporarily secure a tie to said plunger; and means to assemble said flexible fabric having a raised design therein and tie member attached thereto, with the body of a button.
